UNITED STATES PATENT OFFICE.

HARRY A. TAYLOR, OF NEW YORK, N. Y.

DESIGN FOR A GLOVE.

48,334.

Specification for Design.

Patented Dec. 21, 1915.

Application filed July 18, 1914. Serial No. 851,834. Term of patent 7 years.

To all whom it may concern:

Be it known that I, HARRY A. TAYLOR, a citizen of the United States, residing in the borough of Manhattan, city, county, and State of New York, have invented a new, original, and ornamental Design for Gloves, of which the following is a specification, reference being had to the accompanying drawing, forming part thereof.

is a view of the back of a glove, showing my new design.

I claim:

The ornamental design for a glove, as shown.

HARRY A. TAYLOR.
